UNITED STATES PATENT OFFICE.

EDWARD L. SLOCUM, OF LANCASTER, OHIO.

DRUGGIST'S PERCOLATOR.

SPECIFICATION forming part of Letters Patent No. 278,284, dated May 22, 1883.

Application filed March 19, 1883. (No model.)

To all whom it may concern:

Be it known that I, EDWARD L. SLOCUM, a citizen of the United States, residing at Lancaster, in the county of Fairfield and State of Ohio, have invented certain new and useful Improvements in Percolators; and I do hereby declare that the following is a full, clear, and exact description thereof, reference being had to the accompanying drawing, and to the letters of reference marked thereon, which form part of this specification.

My invention relates to improvements in druggists' percolators or filters, in which removable diaphragms are employed to express extracts from solid or semi-solid substances with the aid of menstrua, and the purpose of my invention is to attain this end with the maximum simplicity of construction; and it consists of the particular features herein set forth, and pointed out in the claim. I attain these objects by the means illustrated in the accompanying drawing, in which—

The figure represents an elevation, partly in section, of my device.

Similar letters refer to corresponding parts throughout the view.

A represents a vessel filled with alcohol or other menstruum, which is fed in quantities regulated by cock B through pipes C and D into the cylinder L, made of any suitable material.

E represents a removable cap, whose interior threads engage with exterior threads on a nipple projecting from the top of the cylinder L.

F and G are diaphragms which confine the substance whose extract is desired. They are both vertically movable on the threaded rod H, and are impelled by said rod. The diaphragm F encircles the rod loosely, being kept in place by the substance; but the diaphragm G rests on a threaded boss, I, which is vertically adjustable on the rod by means of the threads thereon. When it is desired to subject the substance to great pressure, before commence-

ing to use the device, the boss I is screwed upwardly, thus bringing the diaphragms together, and should it be required to increase the pressure during the operation, and without disturbing it, it simply becomes necessary to remove the cap E and draw the headed rod vertically upward.

K represents a funnel, through which the extract draining from the cylinder L is conducted into a receiving vessel or bottle, M.

It will be understood that by the use of my device the pressure can be increased at any time without exposing the hand to the liquid, and without in any manner affecting the operation.

Although my device is specially adapted for use by druggists and chemists in obtaining medical or chemical filtrates and percolates, it is obvious that its use is not so limited. On the contrary, it would be useful in lixiviating ashes to make potash, in which case the vessel A would be filled with water; or in extracting dyes from dye-stuffs; or in filtering water through charcoal or silicate; or, in fact, to any use to which a filter may be put.

Having thus fully described my invention, what I claim, and desire to secure by Letters Patent, is—

A cylinder, L, having a headed rod, H, partially screw-threaded and concentric therewith, two movable diaphragms, F G, the latter resting on a boss, I, adjustable on the rod, and the former on the substance confined between them, and a threaded cap, E, on the cover, in combination with a vessel, A, pipe C, nipple D, the former having a cock, B, funnel K, and vessel M, substantially as specified.

In testimony that I claim the foregoing as my own I affix my signature in presence of two witnesses.

EDWARD L. SLOCUM.
